UNITED STATES PATENT OFFICE.

ROSWELL N. BROWN, OF HOOSICK FALLS, NEW YORK.

SASH-CORD FASTENER.

SPECIFICATION forming part of Letters Patent No. 299,199, dated May 27, 1884.

Application filed January 7, 1884. (No model.)

To all whom it may concern:

Be it known that I, ROSWELL N. BROWN, of the village of Hoosick Falls, county of Rensselaer, and State of New York, have invented 5 certain new and useful Improvements in Attachments for Sash-Cords for Windows; and I do declare the following to be a full, clear, and exact description of the same, reference being had to the accompanying drawings, making a 10 part of this specification, in which—

Figure 1 is a perspective of the attachment with the cord in place. Fig. 2 is a view in perspective of a portion of the sash-stile and the cord and its fastening inserted therein. 15 Fig. 3 is a longitudinal cross-section on the line *a a*, Fig. 1. Fig. 4 is a sectional view of Fig. 2 with the cord removed. Fig. 5 is a view in perspective of the cord-holder with the cord removed.

20 Similar letters of reference refer to the same parts in the several figures.

The nature and object of the invention is to furnish a cheap attachment of sash-cord to window-sash, when weights are used to balance 25 the weight of the sash, and one that will not wear out the cord where it is attached to the sash.

A represents a portion of the sash-stile, and into the edge of this is inserted by a mortise 30 a metal piece, B, made with a curved end and a shank or neck, B'. This shank affords protection for the cord and prevents the cord-holder from turning. This piece is furnished with a score to receive the cord, and also a 35 fixed central boss, b. The score is formed between the outer rim of B and the fixed center. Through this fixed center *b* is a hole, *b'*, through which is passed a screw, to hold the attachment and cord in place in the stile, as shown

in Fig. 2. By the simple encircling of the cord 40 around the curved portion of the holder it will be held in place, being snugly fitted therein. The cord leads from the circular portion along the score in the shank portion B', and through a groove cut in the stile to the top of the rail, 45 and thence over the pulley, to receive the weight. In cases where the sash is very heavy it may be necessary to hold the cord more firmly than it will be held by its being curved around the circular portion of the holder. For 50 this purpose I furnish the bottom of the score with one or more points, *c*, which will pierce the cord, and thus make its slipping out impossible.

The cord-holder is inserted into the edge of 55 the stile in such a way as to cover the cord, the bottom of the mortise in the stile forming one side of the cavity in which the cord is held and against which it is clamped.

Having thus fully described my invention, 60 what I claim therein as new, and desire to secure by Letters Patent, is—

1. A sash-cord holder comprising a circular portion having a circular groove and a central boss therein, and a rectangular portion, grooved 65 also, for the reception of a cord, substantially as described.

2. A sash-cord holder having a rectangular grooved part, B', a circular part, B, provided with a circular groove, and points *c*, projecting 70 therein, and a central boss, *b*, provided with a central perforation for the passage of a screw, whereby the device is secured to a window-stile, substantially as described.

ROSWELL N. BROWN.
